UNITED STATES PATENT OFFICE.

LEWIS HETZ, OF NEW YORK, N. Y.

KINETOSCOPE.

956,528.

Specification of Letters Patent.

Patented May 3, 1910.

Application filed April 15, 1909. Serial No. 490,191.

To all whom it may concern:

Be it known that I, LEWIS HETZ, of the borough of Manhattan, city and State of New York, have invented a certain new and 5 useful Improvement in Kinetoscopes, of which the following is a specification.

This invention pertains to an organization for minimizing the noise of operation of a kinetoscope of the intermittent type, to certain 10 improvements in the shutter mechanism of such machines, to means precluding interference with the governing mechanism of the aperture closure when access is had to the machine for the insertion or withdrawal 15 of a film and to a relation of parts such that the shifting of the film actuator with its engaged film for the purpose of positioning the picture properly on the display surface shall simultaneously carry the film an equal 20 distance without causing the latter to thereby under or over-run.

The various features of the invention are disclosed in the kinetoscope illustrated in the accompanying drawings in which—

25 Figure 1 is a side elevation of the machine. Fig. 2 is an elevation, part being broken away, looking from the right in Fig. 1. Fig. 3 is a vertical longitudinal section taken parallel to the axis of the lens tube. 30 Fig. 4 is a cross section taken on the line *a—a* of Fig. 2. Fig. 5 is a perspective detail of the shutter mechanism and associated parts.

Similar characters of reference designate 35 corresponding parts in all figures.

The supporting framework of the illustrated machine embodies a base plate 2 from which extends an upright 2' having secured thereto side plates 3, 3' affording bearing 40 supports for various operative parts.

The present machine being designed for hand operation a hand crank 4 is indicated while a multiplying train is interposed between it and the film actuator. For the purpose 45 of a minimum noise of operation, such train includes an internal gear 5 mounted on a shouldered stud 5' secured to side plate 3'. Hub 4' of crank 4 is rotative on said stud preferably engaging with the internal gear 50 by a clutch 4'.

Included in the aforesaid multiplying train is a gear 6 meshing with the internal gear and secured to shaft 6' journaled in plates 3, 3' and carrying at its opposite end 55 a gear 7 which drives a gear 7' rigid with a spiral gear 8. Shaft 7' of gears 7' and 8 is

journaled in plate 3 and an outboard bracket 7'. Gear 8 meshes with a companion gear 8' on a vertical shaft 9 journaled above and below in bearings 9', 9'' respectively, rigid 60 with plate 3.

The film actuator consists of the usual sprocket wheel 10 the teeth of which engage with notches in the film in the well known manner. Shaft 10' of this wheel is 65 supported on a vertically shiftable carriage comprising side parts 11, 11' and cross piece 11''. As shown this carriage is let into a recess of plates 3, 3' and is guided in its up and down movement by the projecting ends 70 of parallel pins 12, 12 secured to the carriage and slidable in openings in lugs 12' on plates 3, 3'. This carriage may be adjusted to a desired position (to properly place the film with reference to the shutter-controlled aperture presently referred to) by means of a hand lever 13 fulcrumed to a lug 13' on the upright 2' and connected to the carriage by a link 13'' a friction washer 13''' or equivalent device being used to hold the parts in their 75 adjusted position.

The driving shaft for sprocket wheel shaft 10' is designated by 14, a Geneva stop motion 14' being interposed between them whereby a continuous rotary motion of the 85 latter effects an intermittent rotary motion of the former. Shaft 14 is carried by the aforesaid carriage, and preferably provided with a fly wheel 15 and has affixed to it a spiral gear 16 meshing with a companion 90 gear 16' carried by shaft 9. The connection between this latter gear and shaft 9 is preferably a sliding or spline and key way, as 16'' in order that the aforesaid adjusting movement of the carriage shall not there- 95 by turn shaft 14 but effect solely a trans- lational movement of sprocket wheel 10.

The film is held in engagement with sprocket wheel 10 by the usual grooved roller frame 17 journaled on a stud 17' on 100 the carriage and held against or away from the wheel by a spring 17'' adapted to press against a flat surface 17''' on the stud.

A similar sprocket wheel construction is adopted at the top and bottom of the machine, the film being delivered to the former from the supply reel (not shown) and passing from the latter to the take-up reel (not shown). Suffice it to say that shafts 10'' of these sprocket wheels are journaled in bearings 105 in side plates 3 and 3' and are driven by respective gearing 18, 18' from shaft 9 110

in a manner such that they each perform one full rotation for each full rotation of the shaft of the film actuator.

The lens tube is designated by 19, the same being secured to upright 2' in coaxial relation with aperture 20' in film support 20 secured to plates 3, 3'. The film F travels through a groove 20² formed in support 20 past the aperture in the latter and engages 10 with sprocket wheel actuator 10 below as already described.

A retainer in the nature of a hinged leaf 21 serves to hold the traveling film in its guiding groove 20² this leaf being hung on a pintle 21' about which it may be swung to gain access to the groove in removing and inserting films the leaf being locked in its closed position by a catch 21². Opening 21³ in leaf 21 opposite aperture 20' is shown as 20 provided with a closure 22 which while the machine is at rest extends across and obstructs the passage of light through the film and the lens tube. As the machine is operated, however, and the parts gain their predetermined speed the closure swings to 25 one side on its hinge pin 22' leaving the light passage unobstructed. It is desirable also that the opening and closing of leaf 21 shall not be interfered with by the controlling 30 mechanism associated with closure 22. The organization here adopted to meet these requirements embodies a centrifugal governor 23 with its regulating spring 23' associated with shaft 9 and causing the speed-regulated 35 axial positioning of a grooved collar 23² into the groove of which extends the bifurcated end of a hinged lever 24 whose opposite end is also bifurcated and embraces pintle 21' of leaf or door 21. This latter end bears upon 40 a pintle-encircling collar 24^a against whose opposite face bears the bifurcated end of one arm of an angle lever 24' pivoted on door 21 the parts being held in operative relation by a spring 24². The remaining arm of 45 angle lever 24' is connected by a link 24³ with a crank pin on closure 22. Suffice it to say in further explanation that as the speed of shaft 9 increases closure 22 swings farther away from its closing position.

50 Referring now to the shutter mechanism for momentarily shutting off the entrance of light during the intermittent shifting movements of the film, the present mechanism includes a pair of shutters 25, 25 each 55 having superficial dimensions sufficient to approximately shut off the entrance of all light from the source of illumination at some time during its movement across the axis of the lens tube immediately at the 60 front of the aperture in the film support 20. These shutters are adapted to move in opposite directions over a path that carries each shutter from a position above the aperture

to a position below the same and back again, their paths being substantially parallel.

65

The mounting here shown for effecting such movements comprises a pair of pivoted frames one for each shutter and each embracing side arms 25' and a connecting bar 25² to which the corresponding shutter is secured. These side arms are pivoted (one pair within the other) to pins 25³ extending from side plates 3, 3' and are connected to the opposite ends of a rock lever 26 by corresponding links 26', 26'. Rock lever 26 is linked, see 26², to a crank pin 26³ on the aforementioned shaft 7² of gears 8 and 7'. It is evident from this construction that each shutter will perform a double vibration in the arc of a circle for each full turn of 80 shaft 7² and that the path of movement of the shutters departing but little from a straight line will permit the lens tube if desired, to be brought close up to the light aperture in film support 20.

85

Having described my invention, I claim;

1. In a kinetoscope the combination of an apertured film support, a film retainer cooperative with said support and having an opening alined with the aperture in said support, a pintle on which said retainer is hinged, a shiftable closure on said retainer, a centrifugal governor, and a connection between said closure and said governor embodying a sliding connection on said pintle. 95

2. In a kinetoscope, the combination of a hinged film retainer, a hinged aperture closure, a centrifugal governor and a connection between said governor and said closure embodying means for shifting the connection 100 axially of the hinge axis of said retainer.

3. In a kinetoscope, the combination of a pair of vibratory frames each comprising a pair of side arms and a cross bar, shutters secured to the said cross bars, a pair of oppositely extending pins to each of which each of said frames is pivoted, a driving mechanism, and a connection between said frames and said driving mechanism. 105

4. In a kinetoscope, the combination of a pair of vibratory frames each comprising a pair of side arms and a cross bar, shutters secured to said cross bars, oppositely extending pins to which each of said frames is pivoted, a rock arm fulcrumed intermediate its 115 ends, a pair of links extending from said frames to the opposite ends of said rock arm, a driving mechanism, and a crank pin driven thereby and linked to said rock arm.

In witness whereof I have signed this 120 specification in the presence of two subscribing witnesses.

LEWIS HETZ.
